GUARD FOR AN AUTOMOBILE COLUMN LOCK

Billy G. Henry, 1723 W. 60th St.,
Los Angeles, Calif. 90047

Filed June 19, 1975, Ser. No. 588,615

Term of patent 14 years

Int. Cl. D8—07

U.S. Cl. D8—113

FIG. 1

FIG. 2

FIG. 3

FIG. 1 is a perspective view of a guard for an automobile column lock embodying my new design;

FIG. 2 is a top plan view; and

FIG. 3 is an elevational view of the side hidden in FIG. 1.

I claim:

The ornamental design for a guard for an automobile column lock, substantially as shown.
